UNITED STATES PATENT OFFICE.

PAUL RIESS, OF NEW ORLEANS, LOUISIANA.

DESIGN FOR A BAKING-PAN.

50,076.

Specification for Design.

Patented Dec. 19, 1916.

Application filed July 28, 1916. Serial No. 111,951. Term of patent 14 years.

To all whom it may concern:

Be it known that I, PAUL RIESS, a citizen of the United States, and a resident of New Orleans, in the parish of Orleans and State of Louisiana, have invented a new, original, and ornamental Design for Baking-Pans, of which the following is a specification, reference being had to the accompanying drawing, forming a part thereof, and in which—

Figure 1 is a plan view of one side of a baking pan showing my design; and Fig. 2 is an edge view thereof.

The pan consists of two similar mold

members hinged together and presenting, each, a plurality of convex oyster shaped projections arranged radially of a common center, and two similar handle members joined to the respective mold members.

I claim:

The ornamental design for a baking pan as shown and described.

PAUL RIESS.
